UNITED STATES PATENT OFFICE.

LOWELL L. HOLMES, OF CAMBRIDGE, MASSACHUSETTS.

FOUNTAIN PEN.

Application filed August 13, 1923. Serial No. 657,032.

My invention relates to fountain pens; and the object of the improvement is to provide a fountain pen having a conveniently removable pen-point so that different styles of pen-points may be used with the same barrel at the discretion of the writer; or a new pen-point may be substituted for the old pen-point when worn out.

My improvement particularly contemplates the use of pen-points of gold, but also of materials other than gold, thereby materially cheapening the cost of certain grades of fountain pens and at the same time providing means for renewing a corroded pen-point at small cost.

A preferred embodiment of the invention is illustrated in the accompanying drawings forming a part hereof, in which—

Figure 1 is a longitudinal cross section 20 of the fountain pen showing my improved construction; and

Figs. 2, 3, and 4, are perspective views of the disassembled fountain pen parts;

Fig. 2, being the pen-point retaining collar;

Fig. 3, being the pen-point; and

Fig. 4, being a fragmentary section of the barrel.

Similar numerals refer to similar parts throughout the drawing.

Fountain pen 5 is made up of barrel 6, screw retaining collar 7 and pen-point 8. The pen-point 8 is preferably formed with a conical base 9 and a base flange 10. Upon assembling, the conical base fits over the ink conveyor 11 shaped to fit said conical base, and the pen-point is retained in place by the screw retaining collar 7 which wedges the conical base down upon the cone shaped ink

conveyor and at the same time presses against the flange 10. A washer 12 of any suitable material may be provided.

The construction of the invention obviously makes possible the easy changing of pen-points by any unskilled person, as distinguished from the skilled operative now required to change ordinary gold pen points in ordinary forms of fountain pens.

The ink conveyor 11 is preferably integral with the barrel 6 which may be of any approved and well known design. The barrel shown in the drawings is of the non-self-filling type, but a self-filling barrel may be used in connection with the invention.

I claim:

1. A fountain pen having a barrel, a removable pen-point having a conical base, and removable internally coned means for retaining the pen-point on the barrel.

2. A fountain pen having a barrel, a removable pen-point having a conical base, and co-operating means for retaining the pen-point on the barrel.

3. A fountain pen having a barrel, a removable pen-point having a conical base and a flange, and cooperating conical means for retaining the pen-point on the barrel.

4. A fountain pen having a barrel, a pen-point having a conical base and a flange, and co-operating means for retaining the pen-point on the barrel.

5. A fountain pen having a barrel, a conical ink conveyor on the barrel, a removable pen-point having a conical base on the conical ink conveyor, and means for retaining the pen-point on the conical ink conveyor.

LOWELL L. HOLMES.
